UNITED STATES PATENT OFFICE.

WILLIAM J. MORSE, OF ATTLEBORO, MASSACHUSETTS.

DESIGN FOR A BELT BUCKLE.

Application filed September 11, 1922. Serial No. 3,685. Term of patent 3½ years.

To all whom it may concern:

Be it known that I, WILLIAM J. MORSE, a citizen of the United States, residing at the city of Attleboro, county of Bristol, and State of Massachusetts, have invented a new, original, and ornamental Design for a Belt Buckle, reference being had to the accompanying drawing, forming a part thereof.

Figure 1 is a face view of the front plate of a belt buckle, illustrating my new design.

Figure 2 is a transverse sectional elevation on line 2—2 of Figure 1, illustrating my new design.

I claim:

The ornamental design for a belt buckle as shown.

WILLIAM J. MORSE.
